UNITED STATES PATENT OFFICE

93,210

DESIGN FOR A SERVING TRAY OR SIMILAR ARTICLE

Max Friedlander, San Francisco, Calif.

Application June 12, 1934, Serial No. 52,150

Term of patent 14 years

To all whom it may concern:

Be it known that I, MAX FRIEDLANDER, a citizen of the United States of America, residing in the city and county of San Francisco, State of California, have invented a new, original, and ornamental Design for a Serving Tray or Similar Article, of which the following is a specification, reference being had to the accompanying drawing, forming part thereof:—

Fig. 1 is a plan view showing my serving tray; and

Fig. 2 is a perspective view showing the same.

The nature of my design, as fully represented in the drawing, comprises a pair of spaced plates, the upper one being formed in the shape of a double Maltese cross by providing radiating, converging slots at regular intervals around the edge of said upper plate, the portions between said slots

being provided with circular openings within which a glass or the like may be set to prevent the same from being tipped, said glass or other container or article being supported by the lower plate.

The apertures or openings are placed adjacent the edge of the upper plate, leaving an inner central space within which sandwiches, or other appetizers, may be placed, to be served with the liquid refreshment contained in the glasses.

A suitable T-shaped handle is mounted within the approximate center for transportation purposes.

I claim:

The ornamental design for a serving tray or similar article, as shown and described.

MAX FRIEDLANDER.
